United States Patent Office

Des. 216,094
Patented Nov. 25, 1969

216,094

BOTTLE

Edward H. Lawton, Toledo, Ohio, assignor to Owens-Illinois, Inc., Toledo, Ohio, a corporation of Ohio

Filed Dec. 11, 1968, Ser. No. 14,880

Term of patent 14 years

Int. Cl. D9—01

U.S. Cl. D9—140

FIG. 1 is a perspective view of a bottle embodying my new design;

FIG. 2 is an elevational view on a reduced scale, the side opposite that seen being substantially the same in appearance as the side shown;

FIG. 3 is a top plan view thereof.

I claim:

The ornamental design for a bottle, as shown and described.
